UNITED STATES PATENT OFFICE.

JOHN A. JOHNSON, OF MANKATO, MINNESOTA.

LICENSE-TAG HOLDER.

Application filed December 29, 1922. Serial No. 609,667.

To all whom it may concern:

Be it known that I, JOHN A. JOHNSON, a citizen of the United States, residing at Mankato, in the county of Blue Earth and State of Minnesota, have invented a new and useful License-Tag Holder, of which the following is a specification.

This invention relates to display devices and more particularly a combined support 10 and display device especially designed for use in connection with motor vehicle license plates.

The primary object of the invention is to provide novel means for supporting and 15 illuminating the designating characters of the plate.

Another object of the invention is to provide a device of this character wherein a plate may be readily and easily secured in 20 position against rattling.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, may be made within the scope of what is claimed, without departing from the spirit of the invention.

Referring to the drawing:

Figure 1 is a perspective view disclosing a display device constructed in accordance with the invention.

Figure 2 is a front elevational view thereof, the license plate being removed.

Figure 3 is a transverse sectional view through the display device.

Figure 4 is a detail sectional view disclosing the means for securing the removable upper bar of the device.

Figure 5 is a fragmental detail view disclosing one end of the locking bar.

Referring to the drawing in detail, the 45 reference character 5 designates the body portion of the device which is box-like in formation, the same being relatively long and of a size to accommodate the license plate associated therewith.

This body portion is formed preferably 50 of sheet metal and is constructed with a groove 6 extending along the lower edge of the front wall of the body. Lateral grooves 7 are disposed vertically and arranged along 55 the side edges at the forward portion of the body.

At the upper end of the body is an upwardly extended flange 8 arranged along the upper edge of the body and cooperating with the walls of the grooves to hold the license plate indicated at 9, in position.

The license plate 9 is formed preferably of translucent material, the same being supplied with suitable indicating numbers and characters necessary for the use of the same 60 as a motor vehicle license tag, so that the light rays from the illuminating means to be hereinafter more fully described, may be projected through the translucent material to cause the indicating members and 65 characters to be clearly visible in the dark.

Positioned in the groove at one of the edges of the forward portion of the body is a spring arm 10 which has one end thereof secured to a wall of the groove as by means 70 of the bolt 11, finger 12 being carried by the arm 10 to extend through the opening 13 to pass through the opening 14 formed in one end of the movable locking bar 15.

This movable locking bar is inverted U- 75 shaped in cross-section and supports the packing 16 which may be in the form of rubber or other suitable moisture-proof material, so that when the locking bar is positioned as shown by Figure 3 of the drawing, 80 the member 9 will not only be held against movement, but the interior of the body portion will be protected against foreign matter 85 entering the same.

Extending laterally from the body portion at one end thereof is a pin 17 which pin is designed to extend into an opening formed at one end of the locking bar 15 to secure that end of the locking bar against movement. A guard indicated at 18 is secured 90 within the groove adjacent to the arm 10 to engage one end of the member 9 and hold the same in spaced relation with the arm 10 to permit the arm 10 and finger carried thereby, to move inwardly out of engagement with the wall of the opening of the bar 15 when it is desired to position the bar or 95 remove it.

Suitable illuminating means such as the electric lamps 18 may be positioned within 100 the body 5, the lamps being in circuit with a suitable source of electric supply and controlled by a suitable switch not shown.

From the foregoing it will be seen that due to this construction, a translucent license 105 plate may be readily and easily secured in position at the forward portion of the body,

to the end that the designating characters thereon will be clearly visible in the dark.

Having thus described the invention, what is claimed as new is:—

- 5 In a device of the character described, a box-like body portion having grooves formed at the forward portion thereof, a translucent plate adapted to be positioned in the grooves, a locking bar having an opening in one end
10 and adapted to be positioned over the upper edge of the plate to lock the plate to the body portion, a pin carried by the body por-

tion and adapted to extend into the opening at the end of the locking bar, and resilient means at the opposite end of the locking bar ¹⁵ for securing the locking bar against movement.

In testimony that I claim the foregoing as my own, I have hereto affixed my signature in the presence of two witnesses.

JOHN A. JOHNSON.
